UNITED STATES PATENT OFFICE.

MATTHEW G. COLLINS, OF CAMDEN, NEW JERSEY.

DESIGN FOR A KNIFE.

SPECIFICATION forming part of Design No. 25,047, dated January 14, 1896.

Application filed December 14, 1895. Serial No. 572,221. Term of patent 7 years.

To all whom it may concern:

Be it known that I, MATTHEW G. COLLINS, a citizen of the United States, residing at Camden, in the county of Camden, State of New Jersey, have invented and produced a new and original Design for a Vegetable, Fruit, or other Knife, of which the following is a specification, reference being had to the accompanying drawings, forming part thereof.

10 The leading feature of my design for a knife is a scoop on the side of the blade thereof.

Figures 1 and 2 represent views of opposite sides of a knife embodying my design. Fig. 3 represents a top edge view thereof.

15 In the drawings, A designates the blade of a knife, B the bolster, and C the handle thereof.

D designates a scoop whose body is on the side of the blade, near the bolster B, and whose lower portion projects downwardly from said blade and has its point E below the cutting-edge thereof. On the blade, back of the body of the scoop, is the shoulder F.

What I claim is—

The design for a knife substantially as described and shown.

MATTHEW G. COLLINS.
